CLAIM

The ornamental design for a supporting masonry block, as shown and described.

DESCRIPTION

FIG. 1 is a perspective view of a supporting masonry block showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right-side elevational view thereof; and,

FIG. 7 is a left-side elevational view thereof.
